UNITED STATES PATENT OFFICE.

FRANK H. LAKE AND STEPHEN W. SIMS, OF LOYALTON, CALIFORNIA.

HAME-FASTENER.

SPECIFICATION forming part of Letters Patent No. 654,652, dated July 31, 1900.

Application filed March 6, 1900. Serial No. 7,567. (No model.)

To all whom it may concern:

Be it known that we, FRANK H. LAKE and STEPHEN W. SIMS, citizens of the United States, residing at Loyalton, in the county of 5 Sierra and State of California, have invented a new and useful Hame-Fastener, of which the following is a specification.

This invention relates to hame-fasteners, and has for its object to provide an improved 10 device of this character which is particularly designed to facilitate the fastening of the adjacent lower ends of the hames and is also adjustable to accommodate the hames to the collar. It is furthermore designed to house 15 the locking-lever against lateral strain and displacement and to house the spring for actuating the lever entirely within the device, so that the latter may be entirely free from 20 projections in order that the fastener may snugly fit the collar.

With these and other objects in view the present invention consists in the combination and arrangement of parts, as will be hereinafter more fully described, shown in 25 the accompanying drawings, and particularly pointed out in the accompanying claim, it being understood that changes in the form, proportion, size, and minor details may be made within the scope of the claim without 30 departing from the spirit or sacrificing any of the advantages of the invention.

In the drawings, Figure 1 is a sectional elevation of a hame-fastener constructed in accordance with the present invention. Fig. 2 35 is a bottom plan view thereof. Fig. 3 is a detail perspective view of the main part of the fastener.

Corresponding parts in the several figures of the drawings are designated by like characters of reference.

Referring to the accompanying drawings, the numeral 1 designates the main part of the fastener, which is provided with a longitudinal bifurcation 2, which extends for nearly 45 the entire length of this main part and separates the opposite longitudinal side pieces 3. This main part is bowed longitudinally and at the closed end of the bifurcation is reduced in thickness and formed into a hook 50 or eye 4, which is located upon the convex side of the main part, and is also provided with a longitudinal slot or bifurcation 5,

which forms the opposite lips 6 adjacent to the outer side of the main part. At the opposite end each side piece is provided with a bearing-ear 7, which is also located upon the outer convex side of the main part. Although the main part may be formed in one piece, yet it may also be formed in two parts and brazed or otherwise connected at the hooked end 4 thereof.

Pivoted between the opposite bearing-ears 7 is the locking-lever 8, which is provided at its pivoted end with a cam projection 9, that normally is housed between the opposite side 65 pieces of the main part, and the opposite free end of the lever is normally seated within the hook or eye 4 and held between the opposite lips 6, so as to be braced against lateral strain and displacement.

Housed entirely between the side pieces 3 is a leaf-spring 10, which is provided intermediate of its ends with an eye 11 to receive a pin 12, which extends transversely between the side pieces. One end of this spring is 75 beveled, as at 13, so as to overlap and bear against the adjacent beveled portion of the wall of the bifurcation 2, whereby the spring is held in place. The opposite end of the spring is free, and the cam portion of the 80 lever is adapted to bear against the inner side of said free end, so as to be held in both its open and closed positions. By this arrangement the spring is conveniently housed and protected, and by having the pin or fastening 85 12 removable the spring may be conveniently replaced when broken or damaged without requiring the removal of the lever 8.

The other part of the fastener comprises an eye-plate 14, having a hook or loop 15 at 90 its outer end for engagement with one of the hames and also provided with a plurality of eyes or openings 16 to receive the lever and embrace the bearing-ears when the fastener is in place.

In the application of the device the hooks or loops 4 and 15 are engaged with the respective ends of the hames, after which the lever 8 is passed through one of the openings in the eye-plate and then snapped into the 100 position shown in Fig. 1, whereby the two parts of the device are drawn together and the hames are fastened in position.

It will now be apparent that the cam-lever

may be engaged with any of the openings in the eye-plate, so as to accommodate the fastener to the hames and the collar. Moreover, there are no projections at either side 5 of the device, so that the latter may snugly fit the collar, and there is no danger of the fastener becoming accidentally unfastened.

Having thus described the invention, we claim—

10. A hame-fastener, comprising a main part, having a longitudinal bifurcation or slot, the end wall of which is beveled outwardly, a cam-lever mounted within the opposite end of the bifurcation, a leaf-spring housed within the 15 bifurcation, and having a beveled end to

overlap the beveled end of the bifurcation, an intermediate removable fastening passing through the spring and the opposite walls of the bifurcation, the free end of the spring bearing against the cam portion of the lever, and an eye-plate for engagement with the lever.

In testimony that we claim the foregoing as our own we have hereto affixed our signatures in the presence of two witnesses.

FRANK H. LAKE.

STEPHEN W. SIMS.
